UNITED STATES PATENT OFFICE.

WILLIAM HOPKINS AND CHARLES FOCKLER, OF DUBUQUE, IOWA.

STEAM HEATING BOILER.

SPECIFICATION forming part of Letters Patent No. 272,692, dated February 20, 1883.

Application filed November 3, 1882. (No model.)

To all whom it may concern:

Be it known that we, WILLIAM HOPKINS and CHARLES FOCKLER, of Dubuque, in the county of Dubuque and State of Iowa, have 5 invented a new and useful Improvement in Steam Heating Boilers; and we do hereby declare that the following is a full and exact description of the same, reference being had to the accompanying drawings, and to the letters of reference marked thereon.

The present invention relates to steam heating apparatus for buildings, and particularly that class in which the fuel magazine or reservoir is located within an annular boiler.

15 The object is essentially to expose the largest possible amount of surface of the boiler to the action of the heat and products of combustion, in order that but little of the heat passing over such surface may escape utilization.

20 It consists in the novel construction and arrangement of the boiler with relation to the fire-box, and the effective construction and arrangement in such boiler and fire-box of the fuel magazine or reservoir, all as will be more particularly hereinafter described, and pointed out in the claims.

25 For a better comprehension and more thorough understanding of our invention, reference may be had to the accompanying drawings, in which—

30 Figure 1 represents a vertical longitudinal section of the apparatus; Fig. 2, a top plan view of the same; Fig. 3, a vertical longitudinal section of a modification of the apparatus; Fig. 4, a similar view, in part, of a modification of the boiler-extension G of Fig. 1; and Fig. 5, a view, in part, of the adjustable fuel magazine or reservoir, and means by which it is secured in position when raised or lowered.

35 Like letters of reference indicate corresponding parts throughout the drawings.

40 In Figs. 1 and 2, A represents an annular base-plate, having formed within it an ash-pit of ordinary capacity, and supporting the grate B, which may be of any appropriate construction. Above this grate, and upon the base-plate A, rests, and is secured thereon by any proper means, the boiler proper, C, preferably of annular form, and provided at its center and 45 lower portion with the fire-box D, from which a passage, a, leads to a door, b, hinged to the outside of the boiler.

E is the fuel magazine or reservoir, centrally located within the boiler C, and having its lower end extending downward and terminating in the upper portion of the fire-box. The fuel is introduced into the upper larger end, which protrudes out and above the ceiling of the boiler, as shown. There is a space left around this magazine or reservoir of sufficient 55 diameter to receive the fire-brick c c, which surrounds the lower portion of the magazine and protects the same from destruction by heat. This magazine thus located within the boiler is adapted, when occasion requires, to 60 be raised and lowered by means of set-screws d d, which pass through ears e e of the boiler C, and engage each with a slot, f, cut in the sides of the magazine at a point diametrically opposite each other and extending down to 65 the upper terminus of the fire-brick c c.

Between the walls of the boiler C and those of the fire-box D is formed the water space or jacket F, having a connection at neck h with the boiler-extension G, which is supported by 70 the fire-brick walls of the combustion-chamber H. On the side opposite the door b of the boiler c, and opening into the fire-box, are flues i i, extending back and communicating with the combustion-chamber. The heat which 75 is not utilized by the water in the space or jacket F passes off with the gaseous products of combustion and smoke through the flues i i into the combustion-chamber, and thence passes up around the drop-tubes I I, through 80 the flues k k into the smoke-jacket J, presently to be described.

85 The boiler-extension G, located above the combustion-chamber, is constructed with double walls l l, the space between the same being 90 filled with water by means of the connection at h with the boiler proper, C. Within the inner walls of this boiler-extension G is arranged a series of drop-tubes, I I, depending from a horizontal plate, K, located in the upper portion of said boiler-extension and forming a part of the same. These drop tubes open at their upper ends through the horizontal plate K, to which they are attached, and terminate at their lower ends (which are closed) 95 in the combustion-chamber on a line with the flues leading therefrom to the fire-box. These drop-tubes are also filled with water, and the steam generated therein and the several water-

compartments of the boilers ascends and passes into a steam-drum, L, located above the horizontal plate K in the upper portion of the boiler extension G. From this drum the steam is conveyed by any suitable connections to the portions of the building to be heated.

Directly beneath the horizontal plate K, and entirely around the boiler-extension G, is arranged a series of flues, k k, through which the smoke and heat ascending from the combustion-chamber pass off into the smoke-jacket J, with which these flues communicate. These flues are arranged in the manner described for the purpose of allowing the smoke and heat to pass into the smoke-jacket at various points, and thereby maintain an even and uniform draft on all sides of the boiler and between all of the drop-tubes. These flues could be made to communicate with the drop-tubes I I, in which instance the said tubes would be made open at their lower ends and closed at the top, and the heat, instead of passing up between and around them, would pass directly through them, and the water would necessarily be made to circulate around them by any proper construction readily suggested to those skilled in the construction of boilers.

In the modification shown in Fig. 3 a portion of the boiler proper, C, is located within the brick wall of the boiler-extension G, and the connection between these two boilers is made by pipes M and N. The pipes M connect with the water space or jacket F in the upper portion of the boiler C, and, extending upward, open at their upper ends into the steam-drum L. The pipes N connect with this same water space or jacket in the lower portion of the boiler C, and, extending across the floor of the combustion-chamber to the opposite wall of the boiler-extension G, pass up the inner side of the same, and connect also with the steam-drum L. When constructed in this manner the heat and products of combustion circulate around the pipes M and N and the drop-tubes I, and pass up and around the steam-drum L and out of the top of the boiler-extension G. By this means of connection it will be manifest that the shell of the boiler-extension G is greatly relieved from the action of the heat and products of combustion, and the water in the pipes M being heated to a higher degree of temperature than that in the pipes N, a good circulation is obtained. It will also be manifest that the connection between the boiler proper and its extension might

be made in various ways, and that the details of their arrangement might be varied to some extent without departing from the gist of the invention.

It will further be apparent from the foregoing description that the apparatus presents the greatest possible amount of surface to the action of the heat. The component parts are of simple construction and arrangement and properly protected from destruction by heat. The adjustability of the fuel magazine or reservoir enables the same to be raised or lowered when occasion requires, and when so worn as to be unfit for use it can be readily removed and replaced by another without necessitating the removal of other portions of the apparatus.

What we claim, and desire to secure by Letters Patent, is—

1. The combination, in a steam heating apparatus, of an annular boiler, a vertically-adjustable fuel-magazine arranged within the same, a fire-box surrounded by a water space or jacket, and horizontal flues leading from said fire-box and communicating direct with the rear combustion-chamber, as set forth.

2. In a steam heating apparatus, the boiler C and fuel magazine or reservoir E, provided respectively with the set-screws d d and slots f f, by means of which the said magazine or reservoir, when raised or lowered, can be secured in position, substantially as described, shown, and for the purpose set forth.

3. In a steam heating apparatus, the combination, with the annular boiler C, provided with the vertically-adjustable fuel-magazine E, fire-box D, and flues i i, substantially as described and shown, of the boiler-extension G, mounted upon the walls of the combustion-chamber, and having a water-space on its interior and a steam-drum at its upper end, substantially as described and shown.

4. In the steam heating apparatus described, and in combination, the combustion-chamber H, boiler-extension G, drop-tubes I I, smoke-flues k k, smoke-jacket J, and steam-drum L, all constructed and arranged substantially as described, shown, and for the purpose set forth.

In testimony whereof we affix our signatures in presence of two witnesses.

WILLIAM HOPKINS.
CHARLES FOCKLER.
